UNITED STATES PATENT OFFICE.

JOHN P. EUSTIS, OF NEWTON, MASSACHUSETTS.

DESIGN FOR A TEA OR COFFEE POT STRAINER.

SPECIFICATION forming part of Design No. 28,886, dated June 21, 1898.

Application filed May 23, 1898. Serial No. 681,509. Term of patent 7 years.

To all whom it may concern:

Be it known that I, JOHN P. EUSTIS, of Newtonville, in the county of Middlesex and State of Massachusetts, have invented a new and original Design for Tea or Coffee Pot Strainers, of which the following is a specification, reference being had to the accompanying drawings, in which—

Figure 1 is a perspective view of a tea or coffee pot strainer containing my design. Fig. 2 is a sectional view at line 2 2 of Fig. 1.

As shown in the drawings, the leading or material feature of my design consists in the shell-like drip-guard A, mounted at the rear side of and extending slightly below the lower rear portion of the strainer B, the rim b of which is rigidly attached to the drip-guard A

at and near the lateral clip D. The shell or cup like drip-guard A is curved so as to form a space b^2 between the outer rear surfaces of the strainer and the opposed inner surfaces of the guard.

What I claim is—

The design for a tea or coffee pot strainer, substantially as described.

In testimony whereof I have signed my name to this specification, in the presence of two subscribing witnesses, on this 13th day of May, A. D. 1898.

JOHN P. EUSTIS.

Witnesses:

E. A. ALLEN,
EDWARD S. BEACH.
